MOTIVATIONAL DEVICE FOR MUSIC PRACTICE

Anne C. Goldberg, 5530 South Shore Drive,
Chicago, Ill. 60637

Substituted for abandoned design application Ser. No.
228, Dec. 17, 1965. This application June 24, 1968,
Ser. No. 12,929

Term of patent 14 years

Int. Cl. D19—08

U.S. Cl. D25—1

FIG. 1

FIG. 3

FIG. 1 is a perspective view of one side of a motivational device for music practice in accordance with my new design.

FIG. 2 is a perspective view of another side of the device shown in FIG. 1.

FIG. 3 is a top view of the device shown in FIG. 1.

The characteristic feature of my design resides in the combination of the triangular base and the helically arranged wire loop attached thereto as shown.

I claim:

The ornamental design for a motivational device for music practice, substantially as shown and described.
